(57) **CLAIM**

The ornamental design for a heated hose nozzle, as shown and described.

DESCRIPTION

FIG. 1 is a top front perspective view of our new design for a heated hose nozzle;

FIG. 2 is a bottom back perspective view thereof;

FIG. 3 is a left elevation view thereof;

FIG. 4 is a right elevation view thereof;

FIG. 5 is a front elevation view thereof;

FIG. 6 is a back elevation view thereof;

FIG. 7 is a top plan view thereof; and,

FIG. 8 is a bottom view thereof.

The broken lines shown represent features of the heated hose nozzle that form no part of the claimed design.

The area between the dash-dot-dot-dash lines forms no part of the claimed design.
